CLAIM

The ornamental design of a pet treat, as shown and described.

DESCRIPTION

FIG. 1 is a perspective view of a pet treat.

FIG. 2 is a top plan view thereof.

FIG. 3 is a bottom plan view thereof.

FIG. 4 is a front elevation view thereof.

FIG. 5 is a rear elevation view thereof.

FIG. 6 is a side view thereof; and,

FIG. 7 is the opposite side view thereof.
